U.S. Cl. D48—31

FIG.1.

FIG.2.

FIG.3.

FIG.4.

FIG. 1 is a perspective view of a lighting fixture of my new design;

FIG. 2 is a top plan view thereof;

FIG. 3 is a front elevation view thereof; and,

FIG. 4 is a side elevation view thereof the opposite side and rear being identical thereto.

The characteristic features of my design reside in the translucent mirror faces on the front and top of the fixture.

I claim:

The ornamental design for a lighting fixture, substantially as shown and described.
